UNITED STATES PATENT OFFICE.

EMANUEL GEORGE HALVORSEN, OF BROOKLYN, NEW YORK.

AUTOMATIC ALARM.

973,425.

Specification of Letters tent. Patented Oct. 18, 1910.

Application filed June 8, 1909. Serial No. 590,871.

To all whom it may concern:

Be it known that I, EMANUEL GEORGE HALVORSEN, a citizen of the United States, and a resident of the borough of Brooklyn, 5 county of Kings, and State of New York, have invented certain new and useful Improvements in Automatic Alarms, of which the following is a full, clear, and exact description.

10 This invention relates more particularly to an automatic alarm for automobiles.

The primary object of the invention is to provide a simple and efficient device which may be attached conveniently to an operative 15 part of an automobile or other vehicle in such a way that when the vehicle exceeds a certain speed an alarm or plurality of alarms may be sounded so as to notify the attendant of the vehicle and other persons 20 that the speed of the vehicle is in excess of that permitted by law.

Another object of the invention is to provide a simple and efficient device which may be made to automatically ring a bell or operate 25 pneumatic means employed in connection with the usual horn of automobiles.

A further object of the invention is to provide a simple and efficient device which may be used for various purposes.

30 With these and other objects in view, the invention will be hereinafter more particularly described with reference to the accompanying drawings, which form a part of this specification, and will then be pointed 35 out in the claims at the end of the description.

In the drawings, Figure 1 is a section 40 through the casing of the device, showing in elevation one form of alarm mechanism embodying my invention; and Fig. 2 is a front elevation of the device.

The casing 10 may be of any suitable construction and may be attached in any convenient location to an operative part of the 45 vehicle, and said casing may be provided with a bearing 11 at one end thereof and a bracket 12 at the forward part thereof in which is held to rotate a shaft 13, and on said shaft 13 is a pulley or other element 14 by which the said shaft may be rotated from some rotary part of the vehicle. A 50 disk or device 15 is held at one part of the shaft 13 and at or near the other end of the shaft is held a device 16 and connecting 55 said devices 15 and 16 are a plurality of spring members 17 to each of which may be

attached a weight or other part 18 so that when the shaft 13 is rotated the tendency of the weights 18 is to throw the spring members 17 outward, thus causing the device 16 to slide along the shaft 13 toward the disk or device 15. The device 16 has a sleeve portion 19 projecting outward from a disk or collar 19^a and on said sleeve are projections or engaging parts 20. This sleeve 19 is slidingly held to rotate with the shaft 13 by means of a spline and feather or otherwise so that when the speed of the shaft is at a certain rate, the projections 20 will rotate without engaging any other element, 60 but if the speed exceeds a certain rate the said engaging parts 20 are moved inward along the shaft 13 into line with the handle 21. The handle 21 may be pivoted at 22 to the casing 10 and is normally forced in one 65 direction by a spring 23, and said handle or lever 21 has a hammer 24 which is adapted to engage a bell or other sounding element 26 in order that an alarm may be sounded indicating that the vehicle is traveling at a certain speed as for example that 70 permitted by law, and in addition to the alarm 25. I may provide a pumping element 27 adapted to be connected in such a way as to blow the usual form of horn or other 75 alarm. One manner of connecting the pumping element 27 with the horn or alarm is shown in Fig. 2 wherein 27' indicates the horn connected to the pumping element by means of the pipe 27''. As shown, the 80 pumping element 27 has a cylinder 28 in which is movably held a piston 29, and this piston is connected to the rod 30, which by a link 31, is connected to the operating lever 32. The lever 32 is pivoted at 33 to a 85 bracket 34 and said lever is normally out of the path of movement of the engaging parts 20, and is engaged thereby when the speed of the shaft is sufficient to move the device 20 into line therewith, the said lever 32 being moved in one direction by means of a spring 35 or otherwise.

A spring 36 is arranged around the shaft 13 and has one end resting against the disk 19^a of the device 16 and its other end against a collar 37. The collar 37 may be held to the shaft 13 by a set screw 38, and this said collar is adapted to be adjusted along the shaft 13 so that the tension of the spring 36 may be varied in order that the speed at 110 which the shaft is to rotate before the alarm is sounded may be also varied. By adjust-

2
ing the spring 36 a greater resistance may be offered to the movement of the device 16 thereby requiring a greater speed of the shaft 13 before the device 20 will be made 5 to engage the lever of the alarm 25 or the lever of the pumping element forming a part of the second alarm.

It will be understood that the casing may be such that the mechanism will not be accessible except to certain persons, as for example, the police authorities so that said mechanism cannot be tampered with to permit a greater speed to be obtained without sounding an alarm.

15 From the foregoing it will be seen that a simple and efficient device is provided which may be readily attached to an automobile or other vehicle in such a way that the speed of the vehicle may be readily ascertained by 20 the attendant or by others, thus notifying a policeman or other person that the vehicle is exceeding the speed permitted by law; that simple means is provided whereby the alarm may be sounded; that said device may 25 be used for various purposes; and that said device may be made to sound one or more alarms.

Having thus described my invention, I claim as new and desire to secure by Letters 30 Patent:—

1. A device of the character described, comprising a casing, a rotary shaft mounted to rotate within the same, a movable engaging device carried by said shaft, means for

35 moving said device on the shaft, means adjustable on said shaft whereby the position of said engaging device is determined by the speed of said shaft; a pumping element adapted to operate a signal, and a lever for operating said pumping element, said lever 40 being operated by said movable engaging device.

2. A device of the character described, comprising a casing, a rotary shaft mounted to rotate within the same, a movable engaging device carried by said shaft and having 45 its position determined by the speed of said shaft, means for moving said device on the shaft, a pumping element, and means operated by said movable engaging device 50 for operating said pumping element.

3. A device of the character described, comprising a casing, a rotary shaft mounted to rotate within the same, a movable engaging device carried by said shaft and having 55 its position determined by the speed of said shaft, means for moving said device on the shaft, a bell, and a hammer operated by said device, a pumping element and means also operated by said device for operating said 60 pumping element.

This specification signed and witnessed this 5th day of June A. D. 1909.

EMANUEL GEORGE HALVORSEN.
